JONATHAN T. BROWN, OF MARBLEHEAD, MASSACHUSETTS, ASSIGNOR TO
OLIVER A. MILLER, OF BROCKTON, MASSACHUSETTS.

LAST.

SPECIFICATION forming part of Letters Patent No. 725,404, dated April 14, 1903.

Application filed September 11, 1901. Serial No. 75,043. (No model.)

To all whom it may concern:

Be it known that I, JONATHAN T. BROWN, of Marblehead, in the county of Essex and State of Massachusetts, have invented certain new and useful Improvements in Lasts, of which the following is a specification.

This invention relates to a new and useful improvement in lasts; and it consists in the novel features of construction and relative arrangement of parts hereinafter fully described in the specification, clearly illustrated in the drawings, and particularly pointed out in the claims.

Reference is to be had to the accompanying drawings, forming a part of this application, wherein like characters are used to indicate like parts wherever they occur.

Figure 1, in vertical section, shows a last constructed in accordance with my invention, the parts appearing in their operative position. Fig. 2 is a like view showing the heel tipped up to shorten the last with the parts moved out of their operative position. Fig. 3 is a view similar to Fig. 2, showing the heel of the last mounted upon a jack, whereby the heel may be held stationary and the fore part of the last bent down to shorten the last and remove the shoe. Fig. 4 is a detail perspective view of the hinge. Fig. 5 is a top plan view of a last.

1 represents a fore part, and 2 the heel part, of a last. The rear end of the fore part is formed with a vertical face 3 and a forwardly-inclined face 4. The front of the heel part is formed with a vertical face 5, complementary to the face 3 of the fore part, and with a rearwardly-inclined face 6, (see dotted line, Figs. 1, 2, 3,) said face 6 being complementary to face 4 of the fore part. The faces 4 and 6 are located above the pivotal point of the last, while the faces 3 and 5 are located below said pivotal point, so that a V-shaped space is provided above the pivotal point to permit the heel-section to be swung upward and forward to shorten the last in the usual way, while at the same time providing abutting members below the pivot, as is common. The fore part is formed with a vertical recess 7 and two parallel holes 8, extending forward from the forward wall 9 or bottom of said recess.

20 represents a web formed with a pintle-hole 21 and irregular-shaped face 22, said face terminating at the bottom in a finger 23 and being formed at the top with a shoulder 24. The side of the web opposite the face 22 is arranged in the recess 7 and is formed with two lugs 25, arranged in the holes 8 and maintained therein by pins 26, passing crosswise through the last and engaging recesses 27 in the lugs 25. By this construction the web 20, 55 that forms the fore-part hinge member, is firmly and securely maintained in position.

40 represents a plate formed at the bottom of the heel of the last. This plate is formed upon its forward side with a face 41, which 65 constitutes the continuation of the face 5 and is arranged to engage the face 3 of the fore part. (See Figs. 1 and 2.) The bottom surface of this plate forms a part of the bottom surface of the last and is in correct alignment with the bottom surface of the fore part.

43 represents a spindle-socket extending upward from the plate 40. The spindle-socket 43 may be integral with the plate or secured thereto in any desired way. The spindle-socket 43 is formed with a central recess 44, arranged to engage a pin 45, carried by a jack 46, the jack being formed with a lug 47 for a purpose hereinafter described. 80

50 represents two parallel plates of general rectangular shape arranged with their bases upon the plate 40 and with perpendicular sides against the spindle-socket 43. The plates 50 may be integral with the plate 41 85 and spindle-socket 43 or secured thereto in any desired way, the purpose being to have these three sets of parts firmly united together. The web 20 is arranged between the plates 50 and pivoted thereto by a pin 53 90 passing through suitable apertures in the plates 50 and the web.

54 represents a pin extending through the plates 50 in the path of the finger 23 and adapted to be engaged by said finger when 95 the parts are in operative position in order to limit the downward motion of the heel part and, together with the faces 3, 4, and 41, to maintain the last in its operative position.

60 represents a detent pivoted between the 100

plates 50 at their upper sides by means of a pin 61 passing through suitable apertures in the plate and said detent.

62 represents a spring arranged between a pin 63, carried by the plates 50, and the rear end of the detent 60 for the purpose of forcing the front end of said detent yieldingly downward in order to have said detent engage the shoulder 24 of the plate 20 when the heel 2.

10 is thrown down in the position shown in Fig.

1. The parts are so arranged that when the spindle 43 is put upon the jack (see Fig. 3) a lug 47 engages the rear end of the detent 60 and unlocks the same, thereby permitting 15 the relative movement of the fore part and heel part toward each other to shorten the last.

It will be observed that the detent 60 is in an exposed position, with the end that is to be engaged by the lug 47 of the jack in proximity to the outer end of the hollow spindle 43, so that the said detent will be unlocked by the engagement of the lug 47 of the jack without permitting any portion of said jack to actually enter the last. Moreover, since it 25 is not necessary that the lug 47 of the jack shall enter a hole formed in the last it is not necessary to accurately apply the last to the jack, thus saving time in placing the last on the jack.

30 In practice the fore part and heel part are suitably shaped, the recess 7 and holes 8 in the fore part are formed upon suitable jigs, and the plate 20 and its parts secured in position. A similar procedure is followed in 35 the mounting of the plate 40, spindle-socket 43, and plates 50. The arrangement is such that the last is maintained against all strains to which a last is subjected, while at the same time the last may be readily shortened or rigidly locked in operative position, as desired.

40 Having thus explained the nature of my invention and described a way of constructing and using the same, although without attempting to set forth all the forms in which it may be made or all of the modes of its use, I declare that what I claim is—

1. A hinged last, comprising a fore part, a

heel part, a web, parallel lugs upon said web arranged in complementary recesses in said fore part, a heel-plate secured to the heel part 50 and forming the bottom surface thereof, a spindle-socket projecting from said plate, two spaced parallel ears upon said plate in advance of said spindle-socket, said web being arranged between said ears, and pivoted 55 thereto.

2. A hinged last, comprising a fore part, a heel part, a web, parallel lugs upon said web arranged in complementary recesses in said fore part, a heel-plate secured to the heel part 60 and forming the bottom surface thereof, a spindle-socket projecting from said plate, two spaced parallel ears upon said plate in advance of said spindle-socket, said web being arranged between said ears and pivoted thereto, 65 and a part upon the ears arranged to engage a complementary part upon the web to limit the downward movement of the heel.

3. A hinged last, comprising a fore part, a heel part, a web, parallel lugs upon said web 70 arranged in complementary recesses in said fore part, a heel-plate secured to the heel part and forming the bottom surface thereof, a spindle-socket projecting from said plate, two spaced parallel ears upon said plate in advance of said spindle-socket, said web being arranged between said ears, and pivoted there 75 to and a detent carried by said ears and arranged to engage said web above the pivot of the last.

4. A hinged last comprising a fore part, a heel part formed with a spindle-socket, a hinge connecting the fore part and heel part, and a detent for locking said parts in operative position, said detent being located in an exposed 85 position adjacent to the end of the spindle-socket.

In testimony whereof I have affixed my signature in presence of two witnesses.

JONATHAN T. BROWN.
